attorney.

UNITED STATES PATENT OFFICE.

JOHN JACOB KINZER, OF WILDWOOD, PENNSYLVANIA, ASSIGNOR TO PITTSBURG BRAKE SHOE COMPANY, OF PITTSBURGH, PENNSYLVANIA, A CORPORATION OF PENNSYLVANIA.

BRAKE-SHOE.

1,219,462.

Specification of Letters Patent. Patented Mar. 20, 1917.

Application filed December 30, 1915. Serial No. 69,377.

To all whom it may concern:

Be it known that I, JOHN JACOB KINZER, a citizen of the United States, and a resident of Wildwood, in the county of Allegheny and State of Pennsylvania, have invented a new and useful Improvement in Brake-Shoes; and I do hereby declare the following to be a full, clear, and exact description thereof.

10 My invention relates to brake-shoes and has special reference to what is known as "filled shoes" by having a composition of metal in the wheel engaging body thereof.

In this class of brake-shoes it is desired 15 to overcome the difficulties heretofore experienced in forming a brake-shoe, in which the back is to be used over again when the body portion is worn out, and to prevent fracture from expansion and contraction of 20 the same when in use or idle, so that the object of my invention is to provide a cheap, simple and efficient form of a brake-shoe in which the back can be used a number of times when the body is worn down or out, 25 as well as one which will permit expansion and contraction to the extent desired, and one which can be easily and quickly manufactured, assembled and taken apart when desired. A further object of the invention 30 is to provide a shoe of this character in which the body will retain its shape under all conditions, and to provide a body which will be formed of a plurality of parts and securely held together.

35 To these ends my invention consists, generally stated, in the novel arrangement, construction and combination of parts, as hereinafter more specifically set forth and described and particularly pointed out in the 40 claims.

To enable others skilled in the art to which my invention appertains to construct and use my improved brake-shoe I will describe the same more fully referring to the 45 accompanying drawing, in which—

Figure 1 is a plan or back view of my improved brake-shoe;

Fig. 2 is a side elevation of the same;

Fig. 3 is a cross-section on the line 3—3

50 Fig. 2, looking in the direction of the arrows;

Fig. 4 is a view of one of the body sections removed;

Fig. 5 is a cross-section on the line 4—4,

Fig. 2, looking in the direction of the arrows;

Figs. 6 and 7 are side and sectional views, respectively, of another form of the shoe; and

Figs. 8 and 9 are portional views showing the manner of interlocking the blocks and fillers.

Like symbols of reference herein indicate like parts in each of the figures of the drawing.

As illustrated in the drawing A shows my improved brake-shoe, which comprises the supporting back member 1, body or wheel bearing portion 2, and supporting lug 3 through which the brake-shoe is connected in the usual manner to the ordinary approved brake-head or hanger.

The body or wheel bearing portion 2 is formed of a plurality of sectional pieces or blocks 4, preferably of a material such as cast iron or fiber, and the fillers 4' of a composition of frictional material which is well known in the art, thereby forming sections or blocks. These sections or blocks 4 and 4' of different materials, alternate with each other, and the side faces 5 of such blocks 4, which bear against the fillers 4' are tapering inwardly and outwardly from the back wall or strip 1' of the member 1, for the purposes as hereinafter described. The rear of the sections or blocks 4 and fillers 4', are provided with seats 6, within which the supporting back member 1 fits, and which member is formed of metal, preferably steel, so as to be ductile or semi-elastic, and provided with the usual short bearing surfaces 7 having recesses 7', which are formed at the ends of the same, and are adapted to abut against bearings on the ends of the brake-head or hanger, while the usual central or intermediate bearings on said head or hanger are adapted to abut against such back member on each side of the lug 3. The back member 1 is also provided with the end walls or hook portions 1'', which are turned in from the back wall or strip 1' and bear against the side walls or faces 5 on the end sections or blocks in place in the shoe A when formed.

The supporting lug 3 can be connected to the shoe A in any suitable manner, and as shown, is formed of metal, such as steel, and is preferably separate from the back wall 1'. The lug 3 is attached to the back wall 1' of

the back member 1 by having its supporting legs or standards 3' passed through slots 2' in such back wall, with the ends 3'' of such legs bent under such wall, and placed within 5 seats 4^a in the blocks 4 and fillers 4'.

In the formation of my improved brake-shoe A, the back member 1 is cut to shape and size desired, which forms the back wall 1', after which it is pressed or stamped to 10 shape to form the bearing surfaces 7 and end walls 1'', and it is also punched to form the slots 2' in such wall. The sections or blocks 4 are formed and cut to the shape and size desired, and are placed on such back member 1 and spaced between the end walls 1'' on the back member 1 while such back is 15 suitably supported to form the tapered spaces or openings 4'' between the same by the side faces 5 thereon. The lug 3 can now 20 be connected to the back wall 1' in the manner above described, and then while the back 1 and blocks are supported, the composition of frictional material is spread over and between the tapered spaces or openings 4'' 25 between the blocks 4, which material will thereby fill such openings, so that suitable pressure can be supplied to such filled openings to pack and secure such material therein and thereby form such fillers 4', as well 30 as the seats 4^a in the same for the reception of the lug ends 3''. Suitable pressure can now be applied to the inner ends of such sections or blocks 4 while such blocks and such ends of the fillers 4' and back member 1 35 are securely held in dies or any other suitable means, which will bend such back and form the finished brake-shoe by giving to the back and blocks the proper curvature for the blocks to conform to the wheels in forming the body or wheel bearing portion. 2. 40 These blocks 4, when the back 1 is so curved, will be further pressed against the fillers 4' by their side faces 5, by such fillers yielding to the extent desired, and thus said blocks 45 and fillers will be held firmly in place in such back and between the wall 1' and end walls 1'', such end walls being thus drawn more firmly against the end blocks 4 and allowing the back member 1 to form a clamping 50 connection with said blocks and fillers. When the sections 4 and 4' are worn down to the limit they can be removed easily and quickly by supporting the ends 1'' of the clamping back member 1 and then pressing 55 down on the convex side of such member. This will tend to straighten or flatten the curved back and open up the section 4 and 4' to allow such worn out sections to be readily removed, thereby leaving such clamping 60 back in absolutely good condition, and thus enable it to be used over again in clamping similar sections for a number of times.

If desired, the back wall or strip 1' of the back member 1, can be provided with a side 65 lip or flange 9 for extending over the sec-

tions or blocks 4, as shown in Figs. 6 and 7, in order to assist in holding such blocks in place within such member, while the blocks 4 can also be securely locked in position by forming such blocks with a concavo-convex 70 shape on their side faces, as shown in Fig. 8, or can be so secured by being provided with an opening 10 in the same, as shown in Fig. 9, in order to allow the material for forming the fillers 4' to be packed into the same and thereby interlock the fillers and blocks together. 75

It will be evident that the filler blocks or sections can be previously formed to shape and placed between the compressing sections or blocks for being clamped within the back member with such blocks, and said filling material may be plastic. 80

Various other modifications and changes in the design and construction of my improved brake-shoe may be resorted to, without departing from the spirit of the invention or sacrificing any of its advantages. 85

It will thus be seen that after my improved brake-shoes have been in use and 90 have become worn down on their bodies, they can be returned to the manufacturer to enable the back member to be used over again by the removal of the back member therefrom and without injuring or fracturing 95 such back member, which will permit new body members to be used with the same back a number of times, and thereby greatly cheapen the cost of manufacture.

It will also be seen that my improved 100 brake-shoe can be easily and quickly manufactured, assembled for use and taken apart for permitting the continued use of the back member after the body of the same has become worn or for any other cause, while such shoe will also be strong and durable when in use and will be able to withstand knocks or blows of any kind. The shoe will also permit of use until its body is practically worn entirely away, and will have all the substantial advantages of lightness and capability of use on modern high speed trains and especially with steel cars and high brake pressure. The body of the shoe being formed in sections or blocks will also permit of expansion and contraction of the shoe and thereby prevent the same from breaking through heat and cold conditions in the shoe when in use or idle. The shoe being provided with a sectional casing or retainer, it 110 will not become worked or twisted out of curvature by frictional heat, but will stay in full contact with the face of the wheel and consequently give a much higher efficiency in retarding heavy and high speed trains, while 120 such casing or retainer also enables material to be used which will be best suited for the wheel upon which it brakes, and which heretofore has been barred from use by its liability to fracture and other causes. 125

It will also be evident that my improved brake-shoe does not have its back member permanently attached to the body or wheel engaging portion of the same but forms a 5 clamping connection therewith, so that if desired, such back member can be formed of spring metal which should be sufficiently resilient to enable it to be spread open to receive the body portion for clamping the 10 same or removal of said body portion.

What I claim as my invention and desire to secure by Letters Patent is:—

1. A brake-shoe comprising a back member and a body member composed of a plurality of sections or blocks, said back member and blocks being shaped so that in bending said back member to a curve the latter will grip and secure said blocks. 15
2. A brake-shoe comprising a back member and a body member composed of a plurality of interlocking wedge-shaped sections or blocks for engaging the wheel, and means for retaining said blocks in position by end pressure. 20
3. A brake-shoe comprising a back member and a body member composed of a plurality of wedge-shaped sections or blocks, said sections or blocks being formed alternately of two different materials. 25
4. A brake-shoe comprising a back member and a body member composed of a plurality of wedge-shaped sections or blocks, said blocks being formed alternately of metal and a yielding filling material. 30
5. A brake-shoe comprising a metallic back member and a body member connected with said back member, said body member comprising a series of similarly shaped blocks spaced apart and extending across 35 said back member, and a series of filling members, of a different material from said blocks, disposed in the spaces between said blocks and forming, with said blocks, a continuous braking surface, said back member 40 having downturned ends, and being bent to cause said ends to engage and secure the blocks and filling members of said body member. 45
6. A brake-shoe comprising a back member and a body member composed of a plurality of wedge-shaped wheel-engaging sections or blocks disposed side by side to form a continuous member, said sections or blocks being supported by said back member. 50
7. A brake-shoe comprising a back member having a back wall, and a body member composed of a plurality of sections or blocks, said sections or blocks having seats within the same for the reception of said back wall. 55
8. A brake-shoe comprising a back member having a back wall, and a body member composed of a plurality of wedge-shaped sections or blocks, said sections or blocks having seats within the same for the reception of said back wall. 60

9. A brake-shoe comprising a back member and a body member comprising a plurality of sections or blocks, and end walls on said back member for engaging with said sections or blocks to hold the same in place. 70

10. A brake-shoe comprising a back member and a body member composed of a plurality of wedge-shaped sections or blocks, and end walls on said back member for engaging with said sections or blocks to hold 75 the same in place.

11. A brake-shoe comprising a wheel engaging member composed of a plurality of supported wedge-shaped sections or blocks and formed of a material having a lesser 80 wearing quality than the wheel engaged by such member.

12. A brake-shoe comprising a back member and a body member composed of a plurality of wedge-shaped sections or blocks 85 formed of a material having a lesser wearing quality than the wheel engaged by such shoes.

13. A brake shoe, comprising a plurality of sections for forming a wheel engaging 90 portion, said sections being formed of separate disconnected blocks of material extending laterally of the shoe, and separate disconnected fillers of frictional material between said blocks, both having a lesser 95 wearing quality than the wheel, and a back member associated with said sections and having downturned ends for engaging said sections, thereby to retain them in place.

14. A brake shoe comprising a plurality 100 of sections for forming a wheel engaging portion, said sections being formed of separate disconnected blocks of material extending laterally of the shoe, and separate disconnected fillers of frictional material between said blocks, both having a lesser wearing quality than the wheel, and means for holding said sections in place, said holding means comprising a back plate having downturned ends for engaging said sections. 110

15. A brake-shoe comprising a plurality of sections for forming a wheel engaging portion, said sections being formed of blocks of material and fillers of frictional material between the same, both having a lesser wearing quality than the wheel, and a block member connected to said sections for clamping said sections together. 115

16. A brake-shoe comprising a plurality of sections for forming a wheel-engaging 120 portion, said sections being interlocked together.

17. A brake-shoe comprising a plurality of sections for forming a wheel engaging member, said sections being interlocked and formed of blocks of material and fillers of frictional material between the same. 125

18. A brake-shoe comprising a plurality of sections for forming a wheel engaging portion, said sections being formed of blocks 130

of material and a filling of frictional material between the same, and spaces in said blocks for the reception of said filling material to interlock said sections.

5. 19. A brake-shoe comprising a plurality of sections for forming a wheel engaging portion, and means for holding said sections together by end pressure.

10. 20. A brake-shoe comprising a plurality of wedge-shaped sections for forming a wheel engaging portion, and means for holding said sections together by end pressure.

15. 21. A brake-shoe comprising a plurality of sections for forming a wheel engaging portion, and means for clamping said sections together endwise.

22. 22. A brake-shoe comprising a plurality of wedge-shaped sections for forming a

wheel engaging portion, and means for 20 clamping said sections together endwise.

23. A brake-shoe comprising a back having end portions therein, and a body member composed of a plurality of wheel engaging sections associated with said back 25 and clamped between said ends.

24. A brake-shoe comprising a back having end portions therein, and a body member composed of a plurality of wheel engaging wedge-shaped sections associated 30 with said back and clamped between said ends.

In testimony whereof, I the said JOHN JACOB KINZER have hereunto set my hand.

JOHN JACOB KINZER.
